ELECTRON DISCHARGE DEVICE

Application filed December 15, 1923. Serial No. 680,850.

This invention relates to electron discharge devices, and particularly to such devices as are used in connection with telephonic and telegraphic apparatus.

5 Heretofore considerable difficulty has been encountered with microphonic disturbances in connection with electron discharge devices. It has been noticed that these disturbances have occurred when the electron discharge 10 device is in any way mechanically jarred, which obviously may happen in a great variety of ways such as by knocking the device, manipulating the apparatus with which it is mechanically connected, by vibrations of the 15 support or even the building caused by a passing vehicle, and so forth.

The objects of the present invention are to overcome the microphonic disturbances in an electron discharge device; to provide a structure of an electron discharge device substantially incapable of microphonic disturbances created by exterior mechanical movement; to thus increase the efficiency and utility of the 20 electron discharge device; to provide a structure wherein the operative elements are prevented from separately vibrating or oscillating; to minimize the longitudinal distance of the operative elements from the stem or support; to overcome breaking of the filament 25 by distortion; to secure simplicity of construction, manufacture, assembly and economy of materials, and to obtain other advantages and results as may be brought out in the following description.

30 Referring to the accompanying drawings in which like numerals of reference indicate similar parts throughout, Figure 1 is a perspective view of an electron discharge device constructed in accordance with the preferred 35 embodiment of our invention. Fig. 2 is a side view showing the relation between the electrodes, the press, and the electrode supports. Fig. 3 is a top plan view of the press and supports shown in Fig. 2.

40 In said specific embodiment of the invention disclosed in said drawings, the reference numeral 1 indicates the glass casing or bulb as now employed in electron discharge devices which is provided with a suitable base 2 of metal or other suitable material, and which

may be evacuated as heretofore common in the art. Within said casing or bulb 1 is provided the usual stem or support 3 through which the various connections are made from exterior prongs 4 to the operative elements 5 55 within said casing or bulb.

The operative elements in the present disclosure include a tubular plate 6 constituting the anode, which is disposed transversely with respect to the stem or support 3 and 60 preferably as close thereto as is practical in the manufacture of the same. It is to be observed that the mounting of said plate in the structure shown is by means of two wires 7, 7' 65 extending into the end of the stem, one of the wires, as 7, continuing downwardly through the stem for electrically connecting with one of the prongs 4.

Extending longitudinally through the cylindrically formed plate, is a filament or 70 cathode 8 which is preferably centrally disposed with respect to said plate, and proportioned so as to project beyond the ends of the plate. The projecting ends of said filament or cathode 8 are attached to or carried by 75 wires 9, 10 which are bent to pass along the outside of the plate to the stem or support and then downwardly into said support, connecting at their lower ends to two of the prongs 4 so as to admit a flow of current to 80 the filament. It is to be noted that by the structure disclosed and particularly by placing the plate close to the stem or support 3, the wires 9, 10 have practically no length beyond the stem in a direction longitudinally 85 thereof. In other words, the exposed or supporting portion of said wires is reduced to a minimum and particularly reduced to a minimum for parallel portions thereof.

Surrounding the filament in the particular 90 construction shown in the drawings, is a grid 11 in the shape of a coil disposed within the anode or plate 4. Said grid or coil 11 is mounted at its opposite ends at the ends of the plate, to suitable supporting wires 12, 13, 95 which, like the supporting wires for the filament, are appropriately bent to pass along the outside of the plate to the stem or support 3 and then downwardly into said stem. One of said wires, as 12, continues downwardly 100

through the stem to make connection with the fourth of the prongs 4. Here again, attention is to be called to the fact that these supporting wires also have practically no length beyond the stem in a direction longitudinally thereof so that the exposed or supporting portion of said wires is reduced to a minimum and particularly reduced to a minimum for parallel portions thereof.

10. We wish to mention at this point that the usual filament employed in an electron discharge device is generally brittle, and while sufficiently strong to withstand tensile strains, will not withstand shearing stresses. It often 15 happens that vibrations or other disturbances or causes will result in the opposite supported ends not being in direct alignment and as a result break the filament. The above described structure eliminates a large portion 20 of the causes for breaking the filament, but in order to secure a support which is less likely to result in breakage, we preferably provide a resilient support for the filament. In the drawings we have shown a leaf spring 25 14 extending transversely from the filament 8 to the supporting wire 9 and welded, soldered or otherwise affixed to a portion of each. While other forms of springs may be used, the one described and shown has proven satisfactory, it being of such a structure as to not be microphonic and yet adapted to both 30 flex and accommodate torsion.

The structure thus described provides supports for the operative elements, that is, for 35 the plate, filament and grid, which cannot independently vibrate or act in the nature of a tuning fork under mechanical impulse derived from exterior sources. We wish to add, however, that while we have shown the operative elements disposed transversely with 40 respect to the stem, it is within the scope of the invention to provide other disposition thereof so long as the said elements have a common support to which they are attached with minimum intervening supports. And 45 furthermore, we may add that while we have shown and mentioned a "stem" as the supporting means for the operative elements, we wish it understood in connection with both 50 description and claims that we include in the term any support whether it is or is not the conventional stem now known to the art.

Obviously other modifications and changes 55 may be made in the manufacture and use of our improved electron discharge device without departing from the spirit or scope of the invention, and we do not wish to be understood as restricting ourselves to the exact structure shown or described except as set 60 forth in the following claims when construed in the light of the prior art.

Having thus described our invention, we claim:

1. An electron discharge device comprising 65 a stem, lead and supporting wires issu-

ing from said stem, a substantially cylindrical plate arranged transversely with respect to said stem and having mounting means on said plate for receiving wires from the stem substantially tangent to the plate, said mounting means having a length less than the diameter of the plate whereby the plate may be mounted in close association to the said stem.

2. An electron discharge device having a 70 stem with a press portion, a plurality of support and lead-in wires sealed into said press, certain of said supports being stub-like, a cylindrical plate tangentially supported at its central portion from said stub-like supports and having its axis substantially 75 parallel with the edge of said press and at a distance therefrom less than the diameter of said plate.

3. An electron discharge device having a 80 press portion, an electron emitting cathode supported from said press with all the points thereof in close proximity to said press, an anode surrounding said cathode, and stub supports having their ends connected to said 85 stem and the other ends rigidly attached 90 tangentially to said anode at its central portion only to prevent relative movement between said anode and said press, said anode being supported on said supports from the 95 edge of said press a distance less than the diameter of said anode.

4. An electron discharge device having a 100 press portion, an electron emitting cathode supported from said press and arranged substantially parallel to the edge of said press and in close proximity thereto, a control grid surrounding said cathode, and an anode surrounding said control grid, a plurality of support and lead-in wires attached 105 to said stem, certain of said wires being stub-like and having one end thereof rigidly united tangentially to said anode, said wires supporting said anode at a distance from 110 the edge of said press less than the diameter of said anode.
